UNITED STATES PATENT OFFICE.

CASS B. SCHERER, OF CICERO, INDIANA.

BAND-CUTTER AND FEEDER.

SPECIFICATION forming part of Letters Patent No. 289,030, dated November 27, 1883.

Application filed June 22, 1883. (No model.)

To all whom it may concern:

Be it known that I, CASS B. SCHERER, a citizen of the United States, and a resident of Cicero, in the county of Hamilton and State of Indiana, have invented certain new and useful Improvements in Band-Cutters and Feeders; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved band-cutting and feeding attachment for thrashing-machines. Fig. 2 is a top view of the same, with the doors in the top of the frame shown open. Fig. 3 is a longitudinal vertical sectional view on line $z-z$, Fig. 2. Fig. 4 is a cross-sectional view on line $x-x$, Fig. 2, and Fig. 5 is a similar view on line $y-y$, Fig. 2, seen from the direction opposite that of Fig. 4.

Similar letters of reference indicate corresponding parts in all the figures.

My invention has relation to band-cutting and feeding attachments for thrashing-machines, and has for its object, in common with others, first, to effect the severing of the band, cord, or other material around the sheaf when thrown into the hopper, and, second, to facilitate the feeding of the wheat or other grain to the thrasher; and it consists in the improved construction and combination of parts of the same, as will be hereinafter more fully described and claimed.

In the accompanying drawings, A represents the frame or casing which supports the several parts of my improved band-cutting and feeding attachment for thrashing-machines, which is so constructed that it may be readily attached to any thrashing-machine of ordinary construction.

B indicates the main drive-shaft, which receives its motion through a belt, preferably from the thrasher, which passes around a cone or speed pulley, C, on one end of the shaft B. To the same end of the drive-shaft is also affixed a pulley, D, and a pinion, E, while to the opposite end of the drive-shaft is affixed a pulley, F, as shown in the drawings. The teeth of the pinion E mesh with the teeth of

a gear-wheel, G, which is fastened at right angles to the pinion upon a stud axle or spindle, H, projecting from the side of the casing. A pulley, I, is bolted upon the side of the gear-wheel G, so as to receive its motion from the gear-wheel, the pulley and gear-wheel being concentric. The straw-carriers J K consist of endless traveling aprons or belts, supported, the apron J on rollers N O and the apron K on rollers L M, the ends of the rollers fitting into journal-boxes in the sides of the frame or casing A. One of the ends of the rollers L and N extends through the side of the frame A, the roller L having fastened to its outer end a pulley-wheel, P, while the roller N has two pulleys, Q Q', fastened to its outer end, as shown at Fig. 2. An endless belt, R, passes around the pulley I, secured to the gear-wheel G, and the pulleys P and Q on the ends of the shafts or rollers L and N, the belt moving in the direction indicated by the arrows. As the gear-wheel G is rotated by the pinion E on the drive-shaft B, the belt R transmits its motion to the rollers L and N, thereby causing the endless aprons J K to travel toward the center of the frame, for the purpose hereinafter specified.

W represents a disk or pulley wheel, which revolves upon a stud-axle or spindle, T, projecting from the side of a cross-beam, X, which forms a part of the frame A, and extends above the endless apron K, as shown in Fig. 3 of the drawings. To the outer surface of the disk or wheel W is attached an adjustable knife, Y, adapted to cut the bands of the sheaves or bundles which pass below it on the traveling apron K. The knife Y is fastened adjustably upon the face of the wheel W by a bolt or pivot, A', passing through its heel, while a thumbscrew, B', passes through the knife near its heel to fit into one of a series of screw-threaded apertures in the face of the disk. By this arrangement the cutting-edge of the knife can be adjusted at any desired angle, whereby I am enabled to take up wear of the cutting-edge. A similar disk or wheel, S, is affixed upon a stud-axle projecting from a cross-beam, U, extending above the endless apron J at the other end of the frame A, a knife, U', being adjustably fastened upon the outer face of the disk S by means of a pivot, A", and

thumb-screw V, in the same manner as that in which the knife Y is fastened to its disk W. The disk or pulley wheels W and S are rotated by means of endless belts C'D', the belt C' fitting 5 around the pulley D on one end of the drive-shaft B and passing over guide-pulleys E', F', and G', hung in suitable bearings on the outside of the frame A, and around the pulley W, while the belt D' fits around the pulley F on the other end of the drive-shaft B and passes over guide-pulleys H', I', and J', hung in suitable bearings on the outside of the frame A, at its other end, and passes around the pulley S.

10 K' indicates a pulley-wheel revolving upon a stud-axle or spindle, L', projecting from the side of the casing. From the face of the disk K' projects a wrist-pin, L'', to which is attached the end of a pitman, M', the other end 15 of which is pivoted to the end of a lever or connecting-rod, N', which passes through a slot, O', in the side of the casing A, and is held in position by a bolt or pivot, Q'', upon which it turns. The end of the lever N', which 20 projects inside of the frame or casing A, is pivoted to the middle of a shaking-bar, R', which is provided with upwardly-projecting teeth or fingers S', the shaking-bar being of such a length that its ends pass through the slots T' 25 in the end walls of the lower part of the frame A. An endless belt, U'', passes around the pulley-wheel K' and the pulley Q' on the end of the roller N, so that as the roller N is revolved by the belt R, previously referred to, 30 the pulley Q' will transmit its motion to the pulley K', to which the end of the pitman M' is attached by the wrist-pin L', the pitman M' and the lever N' serving to rock or oscillate the shaking-bar R'. An endless apron, V', 35 supported upon the central part of the drive-shaft B, and a roller, W, having its ends journaled in the end walls of the lower part of the frame A, below the shaking-bar R', serves to convey the grain to the thrashing concave and 40 cylinder.

X' X' indicate the hoppers, which are attached to the top of the frame A, one above each of the traveling aprons J K. Y' Y' represent hinged doors in the top of the frame A, between the hoppers X', through 50 which access may be obtained to the inner working parts of the attachment.

Z' Z' indicate slots in the top of the frame A, to permit the free passage of the revolving knives U' and Y.

The operation of my improved band-cutting and feeding attachment for thrashing-machines is as follows: The sheaves are laid in the hoppers X', when they fall crosswise or 55 at right angles upon the endless aprons J and

K, and are carried under the revolving knives U' Y, which cut the bands of each sheaf as it passes beneath it. The bundles then fall crosswise or at right angles upon the shaking-bar R', which stirs up and loosens the bundles, after which they fall lengthwise upon the endless traveling apron V', which conveys them to the thrashing concave and cylinder.

From the foregoing description, taken in connection with the accompanying drawings, 70 the construction and operation of my improved band-cutting and feeding attachment for thrashing-machines will readily be understood without requiring further explanation.

By constructing the band-cutting portion of 75 my attachment double—that is to say, with two hoppers, two revolving knives, and two endless aprons for carrying the sheaves under the said knives—I enable the thrashing-machine to be fed from two stacks at once, there- 80 by effecting a great saving in time.

Having thus described my invention, I claim and desire to secure by Letters Patent of the United States—

1. The combination, in a band-cutting and 85 feeding attachment for thrashing-machines, of the aprons J and K, shaking-bar R', having upwardly-projecting teeth or fingers S', adapted to loosen and separate the sheaves which fall upon it crosswise or at right angles from 90 the aprons J and K, lever N', pitman M', pulley K', having wrist-pin L'', endless belt U'', pulley Q', means or mechanism by which a rotary motion may be imparted to said pulley, and apron V', all arranged to operate substantially in the manner and for the purpose shown and set forth.

2. The combination of the frame A, drive-shaft B, having a speed or cone pulley, C, pulley-wheels D F, and pinion E, guide-pulleys E' F' G' and H' I' J', disks or pulleys S W, adjustable knives U' Y, endless belts C'D', gear-wheel G and pulley I, rollers N O and endless apron J, rollers L M and endless apron K, pulleys P Q, endless belt R, pulley Q', pulley K', having wrist-pin L'', endless belt U'', pitman M', lever N', and shaking-bar R', having upwardly-projecting teeth or fingers S', roller W', and endless apron V', adapted to travel around the middle part of the drive-shaft B and the roller W', all constructed and arranged to operate substantially as and for the purpose shown and described.

In testimony that I claim the foregoing as my own I have hereunto affixed my signature in 115 presence of two witnesses.

CASS B. SCHERER.
